UNITED STATES PATENT OFFICE.

FRANK O. WOODLAND, OF WORCESTER, MASSACHUSETTS, ASSIGNOR TO ECONOMIC MACHINERY COMPANY, OF WORCESTER, MASSACHUSETTS, A CORPORATION OF WEST VIRGINIA.

LABELING-MACHINE.

1,113,856.

Specification of Letters Patent. Patented Oct. 13, 1914.

Application filed March 7, 1913. Serial No. 752,566.

To all whom it may concern:

Be it known that I, FRANK O. WOODLAND, a citizen of the United States, residing at Worcester, in the county of Worcester and State of Massachusetts, have invented new and useful Improvements in Labeling-Machines, of which the following is a specification, reference being made therein to the accompanying drawings.

10 My present invention relates to a novel arrangement of label-wiping appliances more especially adapted for rotary labeling machines of the class described in my previous application, Serial No. 720,913, or 15 machines wherein the bottles or articles to be labeled are caused to travel, in upright position, between and past stationed wiper-devices, in a continuous successive order; the prime object being to render the machine 20 more convenient, efficient and practically economical.

Another object of my invention is to provide an equipment of wipers assembled as a compound unit, in a manner to be put 25 on and taken off the labeling machine as a unit, or all at a single operation, without disarranging the relative location or combination of the wipers in the complete set; thus affording a method and means whereby 30 wiper-appliances adapted for one kind or size of bottles or articles, can be readily exchanged, upon the machine, for wipers adapted for another kind, size or form of bottles or articles, without loss of time in 35 making the exchange, or requiring particular attention to the adjustment of the individual wipers or their actuating devices.

Another object is to provide in a labeling machine of the character described, and in 40 combination with means for gumming and presenting labels, and a rotary or moving carrier adapted for advancing a series of bottles or the like in successive order; an improved wiper-mechanism comprising automatically 45 movable wipers and means for operating the same controlled or actuated by a series of studs or contacting means, carried upon or in connection with the moving table or bottle-carrier, as more fully 50 hereinafter explained.

Minor objects and features of the invention are set forth in the following detailed description, the subject matter claimed being definitely expressed in the summary.

55 As illustrated in the drawings, Figure 1 represents an elevation view of such parts

of a rotary-carrier label-affixing machine as will show the location and general arrangement of my improved wiper-mechanism with respect to other portions of the machine. Fig. 2 is a back view of my wiper unit compound; a section of the rim portion of the rotary carrier table, and means for actuating the movable neck-label wipers. Fig. 3 is a side view of the same looking in the direction indicated by the arrow S³. Fig. 4 represents a horizontal section, at the position of line X X on Fig. 2, showing the body-label wipers, as with a bottle passing through. Fig. 5 is a top plan view showing the movable neck-label wipers. Fig. 6 is a detail horizontal section of the lower end of the actuating lever and the contacting detent and cam. Fig. 7 represents a modification wherein movable wipers are given a horizontal instead of a vertical movement.

In the general structure of the labeling machine to which my invention is applied in the present instance, the numeral 10 indicates the main standard or column of the frame; 11 the arm or frame member that supports the upper operating parts; 12 a centrally supported horizontally rotatable table or carrier having thereon rests 14, or 15 means for sustaining bottles or the like in approximately upright position and advancing the same in a circular path and in successive order from a place of reception to a place of discharge.

2 indicates the table-operating gear; 3 a driving pinion meshing therewith and mounted upon an operating shaft 5 having the pulley P and clutch C, or other suitable driving appliances arranged thereon, 35 for applying power and motion.

15 indicates a label-supply holder; 6 a pair of label-carrying pickers that transfer the labels from said holder to the face of the bottle; 16 a picker-carrier; 9 a picker 40 actuating means; and 7 indicates the gripping devices that clamp the labels to the bottle and assist in stripping them from the pickers.

A portion of the glue-reservoir and its 45 delivering-roll are indicated at G, and the glue-distributing roller that spreads glue upon the pickers is shown at D. These rolls are mostly omitted from the drawings, the better to illustrate the relation in which the labels L are presented to the bottle B.

The above enumerated parts may all be

arranged for operation substantially as illustrated herein, or as described in my prior application for Letters Patent therefor, or in any approved manner; since such portions of the machine are not in themselves the subject of my present invention, but are included to illustrate the combination therewith of the improved means and to afford a clearer understanding of the nature and relation of my claimed invention in its practical embodiment.

In accordance with my present invention there is provided a bifurcated or inverted U-shaped plate or straddle-frame 19 upon the respective limbs of which the pairs of body-label wipers 20 and neck-label wipers are mounted and secured in their proper relative order and positions, as best shown in Fig. 2. The body-label wipers 20 are, for common style labeling purposes, firmly attached to the plate and project inward from the opposite limbs thereof, but may in any instance, if desired, be made movable in a manner similar to that herein described for the neck-labels. The neck-label wipers 21, which are arranged to effect a variable wipe, are attached to arms or levers 23 pivotally supported upon the respective limbs of the plate 19 by suitable studs, as indicated at 24, so as to swing the wiper heads up or down, outward or inward, while acting upon the label.

Numeral 25 indicates an operating lever fulcrumed at 26 upon the outer limb of the plate or frame 20. The upper part of said operating lever is joined, by a pivotally connected link or joint member 27, with one of the wiper-arms 23; while its lower end is adapted to receive contact of a stud or controlling member 30 carried upon the rim or under face of the bottle-carrier element. A spring 29 is provided to act upon the lever 25 for retracting said lever and the connected wipers to normal position; also means 31 for limiting the movement. The lever 25, at its lower end, is preferably extended beneath the peripheral portion of the rotatable bottle-carrier 12, and is provided with a suitably shaped cam member 28, (see Fig. 6) and a series of projecting pins, studs or equivalent devices 30 are fixed in the rim or under surface of the carrier table, which contact with the cam member, and by movement of said lever control the action of the movable wipers. The pins or studs are located in such relation to the bottle supporting rests that the wipers will be actuated while the successive bottles pass between them.

60 34 indicates a cross connection lever for causing the wipers to move in unison and in right and left order. Said lever is fulcrumed at 33 upon the plate or frame 19, and its ends are arranged to engage with the wiper arms 65 by suitable slots and pivot studs. As shown

in Fig. 2 the wipers are arranged to give a downward oblique wipe; but if an upward oblique wipe is desired then the pivots of the link 27 are placed in the holes 17, thus bringing the link below the fulcrum axis 24 70 of the wiper arms.

The wiper faces or portions that contact with the labels, are shown as made of rubber; but it will be understood that groups of spring-pressed metal fingers, brushes, or any suitable or well known kind of wiper face can be employed in lieu of rubber. The entire set or group of wipers, including body-label wipers and neck-label wipers, together with the cross-connecting lever, actuating lever and springs, are made up and assembled upon the bifurcated plate or frame 19 as a compound unit, and adapted for attachment of said plate to, and its detachment from the machine frame 11, by releasable fastening means or bolts 8, without disturbing the relation of the wipers and their accompanying devices in respect to each other, or the uncoupling of lever connections and pivot joints. This construction renders it practicable for the manufacturer of the labeling machines to make up the wiper-unit-compound complete, with wipers adapted for any one of the various styles, sizes, forms or kinds of labels, bottles or packages as desired in practice, and to affix such wiper-unit-compound to the labeling machine according to the style required, simply and expeditiously by the two bolts 8. Also to quickly change the labeling from one style to another by removing, as a unit, one plate 19 with its set of wipers intact thereon, and substituting in its place another wiper-unit-compound having the proper style of wipers. This exchange can 100 be readily effected by any person, or as often as desired, and without special attention and labor of adjusting the individual wiper members; an especial advantage being that it can be done without having to disconnect any toggle links, pivot joints or levers; since all such parts go with the disconnection of the plate or supporter 19, and there being no attachment between the operating means and the actuating device on the 110 carrier, there is no change of the studs or any thing on the carrier that has to be changed or adjusted at the time.

The modification, Fig. 7, illustrates the wipers adapted to move inward as forlapping the ends of a label completely around the bottle or article to which it is applied. In this case the pivots 24 are disposed in upright instead of horizontal position. The modification also shows an instance in which 125 each individual wiper is provided with an operating means or lever 25 and 25^x, that are independently actuated by the studs 30 on the moving bottle-carrier; the operation thereof being substantially as above de- 130

scribed, except that one of the wipers acts a little in advance of the other.

What I claim and desire to secure by Letters Patent, is:

- 5 1. In a labeling machine, in combination, a movable carrier, means thereon for supporting bottles or the like upright while moving with said carrier, a wiper-supporting plate bridging the path of the carrier,
- 10 10 a pair of movable wiper-carrying heads mounted on said wiper-supporting plate, wipers attached to said heads between which the bottles pass, means for operating said movable wiper devices, and actuating 15 devices connected with said movable carrier for imparting motion to said wiper operating means.
2. In a labeling machine, in combination with a rotatable carrier or table provided 20 with means for supporting bottles or the like thereon in upright position; of a pair of movable wipers, a connection for effecting opposite movement of said wipers in unison, an operating lever for imparting 25 motion thereto, and a contacting device carried by said rotatable table for actuating said operating lever at a predetermined position in the rotation.
3. In a labeling machine, the combination 30 with a movable bottle-carrier provided with means for supporting and advancing bottles or the like; of a wiper-supporting element, means for attaching said element to the machine frame, a pair of oppositely disposed wiper-carrying arms pivotally mounted 35 upon said supporting element, and means actuated from said bottle-carrier, for moving said wipers while the bottle passes between them.
- 40 4. In a labeling machine, a wiper-unit compound consisting of an inverted approximately U-shaped supporter having the several wiper elements mounted thereon in their predetermined working relation in respect to each other, said supporter adapted 45 for ready attachment to and detachment from the machine frame without disturbing the relation of the wiper elements in respect to each other upon said supporter.
- 50 5. In a labeling machine, the combination with means for gluing and presenting labels at a predetermined position across the path of the bottles, a continuously moving bottle-carrier having means for supporting 55 a series of bottles or the like thereon in upright successive order, gripping devices that move with said carriers, for respectively clamping the labels as presented to the bottles, and a wiper compound comprising an 60 overhanging bifurcated supporter straddling the path of the bottles, and having

pairs of wipers mounted upon its depending limbs, between which the bottles are successively passed.

6. In a labeling machine, in combination 65 with means for gumming and delivering labels, a movable carrier having means thereon for supporting bottles or the like in upright position, and to travel in successive serial order along a predetermined path 70 with the movement of said carrier, means for gripping the delivered labels to the respective bottles, means for moving said carrier, a wiper-supporting element stationed athwart the path of the advancing bottles, 75 a wiper set mounted thereon, including swinging wiper-members, means mounted on said supporting element for automatically moving said swinging wipers, and an unconnected controlling means carried 80 upon said bottle-carrier for coactingly engaging with said wiper-operating means, the engaging parts having shaped contact surfaces, conformed for imparting a predetermined quality of motion to the movable 85 wipers.

7. In a labeling machine, the combination, 90 of a bottle-traveling carrier, a stationed wiper-supporting frame overhanging said carrier, a pair of automatically adjusting 95 wipers movably mounted thereon, between which the bottles are conveyed by said carrier, wiper-operating connection mounted upon said wiper-supporting frame, and an actuating member fixed on the bottle-traveling 95 carrier and coacting with said wiper-operating connection for moving and controlling said wipers as the bottle passes between them.

8. In a labeling machine, in combination 100 with a rotary bottle-carrier having means for the upright support of bottles thereon; means for gluing and delivering labels, and means for centrally gripping the labels to the bottle, a wiper-unit comprising a bifurcated supporting plate having body-wipers mounted thereon, and neck-wipers provided with arms pivotally mounted thereon, said arms connected for relatively opposite movement of said neck-wipers; an 105 actuating lever fulcrumed on said plate, its upper end linked to the wiper arm, means for retracting said lever, and a series of devices upon said bottle-carrier for contacting with said wiper-actuating lever. 110

Witness my hand this 5th day of March, 115
